UNITED STATES PATENT OFFICE

OSCAR D. BRINSER, OF RICHMOND, VIRGINIA

ADJUSTABLE SCYTHE BLADE FASTENING

Application filed January 15, 1932. Serial No. 586,896.

This invention relates to fastening means for securing a scythe blade to the handle or snath, as it is commonly called, and it is particularly designed to include adjusting means which will permit varying the position of the plane of the blade with respect to the handle so as to accommodate the tool to different users. It consists of certain features and elements of construction in combination as herein shown and described, and as indicated by the claims.

In the drawing:

Figure 1 is a side view of the end portion of a snath inverted as compared with the position of use, and showing blade fastening means thereon embodying this invention.

Figure 2 is taken as a detail section at line 2-2 on Figure 1.

Figure 3 is an end view taken as indicated at line 3-3 on Figure 1.

Figure 4 is a detail perspective view of the adjusting wedge.

Figure 5 is a face view of the end of the snath and a fragment of the scythe blade showing the tang of the blade secured by the clamping ring to the snath.

Figure 6 is a side elevation of a modified form of wedge member.

The drawing shows simply the end portion of the wooden handle or snath, 1, and a part of the scythe blade, 2, including the tang, 3, which is secured to the handle, 1, by the fastening embodying this invention. The fastening includes a ferrule portion, 4, encircling the extreme end of the snath, 1, and having preferably integral with it a grooved plate, 5, overlying a flattened portion, 6, of the snath, and a toothed plate, 7, which overlies an opposite flattened portion, 8, of the snath. A heel plate, 9, against which the tang, 3, is secured, is formed with ears or lugs, 10, by which it is pivotally engaged with trunnions, 11, projecting from the ferrule, 4. The plate, 9, is thus adapted to swing toward and from the plate, 7, at its

end remote from the pivots, 11, so as to vary its angular relation to the snath, 1.

The plate, 9, includes an upstanding integral lug, 12, for engagement with the heel portion, 13, of the tang, 3, in the usual manner, and a clamping ring, 14, encircles the entire fixture, including the tang, 3. The ring, 14, is preferably formed with a flat portion, 15, which engages the outer face of the tang, 3, and at the opposite side the ring is provided with a threaded boss, 16, carrying a set screw, 17, which impinges upon the plate, 5, in the longitudinal groove, 5^a, thereof for producing a clamping pressure of the flat side, 15, of the ring against the tang, 3. In addition to the heel-engaging lug, 12, the plate, 9, has the usual plurality of square apertures, 18, to receive the down-turned lug, 3^a, at the end of the tang, 3, so that shifting this lug from one to another of the apertures, 18, changes the angular relation of the edge of the blade to the snath, 1.

In most, if not all, previous constructions, the plane of the scythe blade with respect to the snath has been fixed. This might give the correct working angle for a man of a given height, or with a given reach, but would not be right for a shorter man or a taller man, or for one having longer arms. Where the same person was to use the scythe continuously, this has often been corrected by twisting the blade at the portion where the cutting edge joins the tang, 3. Of course, this adjustment could not be changed many times without injury to the blade; furthermore, it is frequently desirable to vary the angle of the blade with respect to the snath, depending upon whether the class of work permits a long sweeping stroke or demands a short hacking stroke. To remedy this situation I provide an adjustable wedge, 20, which is preferably formed with teeth on one surface to engage the teeth of the plate, 7, and whose opposite face is disposed against the plate, 9. This wedge, 20, may be shifted

along the plate, 7, to vary the angle of inclination of the plate, 9, with respect to the snath, 1, and since the tang, 3, of the scythe blade is held firmly against the outer face of the plate, 9, by the clamping ring, the scythe blade is thus swung laterally in response to any change of angle of the plate, 9. Thus the plane of the blade may be shifted as desired with respect to the snath to accommodate different users and different classes of work.

The arrangement of the plates, 5 and 7, as integral portions of the ferrule, 4, provides an unusually sturdy construction, and in view of the engagement of the flattened portions, 6 and 8, with correspondingly shaped sides of the ferrule, 4, the fitting is firmly anchored to the snath by a single bolt or rivet, 19, which practically eliminates the possibility of splitting the wood, either in assembly or in use of the tool.

Preferably, for lightening the construction, the wedge member, 20, has the metal eliminated from its middle portion, leaving the piece of square-cornered U-shape, as seen in Figure 4; and for the same reason the middle portion of the plate, 7, may be omitted, so that the toothed area is in the form of two lateral rows of teeth registering with the toothed arms of the U-shaped wedge, 20.

Incidentally, it may be noted that since the adjustability of the heel plate, 9, about its pivots, 11, results in a change of angle between the heel plate and the toothed plate, 7, a straight-sided wedge of fixed angle, as shown in Figure 4, will fit perfectly between the two plates at only one position of adjustment; Figure 1 indicates that this wedge fits only approximately at other points in its range of movement. Therefore, as an alternative, I may prefer to form the wedge member as shown in Figure 6 at 20^a, with an upwardly convex portion, 20^b, designed for contact with the under surface of the hinged heel plate, 9. The corrugations or teeth of the member, 20^a, will serve the same function as in the form shown in Figure 4, namely, to interlock with the teeth of the plate, 7, and prevent slipping of the wedge member.

I claim:

1. In combination with a snath, a scythe blade fastening comprising a heel plate and a ring encircling the snath and said plate for securing the tang of the blade by clamping engagement with the tang interposed between said ring and the plate, said ring being provided with a set screw adjustable toward and from the snath at the side opposite said heel plate, said plate being hinged to the snath at an axis transverse to that of the end portion of the snath, and adjusting means for varying the angular relation of said hinged plate to the snath.

2. In combination with a snath, a scythe blade fastening comprising a pair of plates

secured to opposite sides of the end portion of the snath, a ring adapted to encircle said portion with the tang of the blade interposed between the ring and one of the plates, a set screw in the ring disposed to impinge against the other plate to secure clamping engagement of the ring with the tang, the plate which engages the tang being hinged to the snath adjacent the extreme end thereof with the opposite end of said plate free to swing toward and from the snath, and adjusting means for variably fixing the angular relation of said plate to the snath.

3. In combination with a snath, a scythe blade fastening comprising a ferrule tightly encircling the end of the snath with two plates extending therefrom along opposite sides of the snath, a clamping ring dimensioned to encompass said plates, and a tang of the blade, said ring having a set screw positioned to impinge against one of the plates at the side of the ring opposite that which engages the tang, the other plate having a corrugated outer surface and the third plate hinged to said other plate at one end with its opposite end free to swing toward and from said plate, and a wedge corrugated on one side for engagement with the corrugations of the said plate and adjustable between said plate and the third plate for varying the angular relation of the hinged plate to the other, and thus varying the angular relation of the tang and blade to the snath.

4. In combination with a snath, a scythe blade fastening comprising a heel plate hinged to the snath adjacent the extreme end thereof for angular adjustment in respect to the snath, adjusting means for determining the angular relation of said plate to the snath, and fastening means which simultaneously secures the tang of the scythe blade to the plate and fixes said plate at the adjusted angle.

5. In combination with a snath, a scythe blade fastening comprising a heel plate hinged to the snath adjacent the extreme end thereof for angular adjustment in respect to the snath, adjusting means interposed between said plate and the snath and movable longitudinally for varying the angular relation of said parts, together with a scythe blade disposed with its tang against the outer face of said hinged plate, and clamping means embracing said snath and the tang and plate with the adjusting means interposed, whereby the tightening of said clamping means binds all of said parts in adjusted relation.

6. In combination with a snath, a scythe blade fastening comprising a heel plate hinged to the snath adjacent the extreme end thereof for angular adjustment in respect to the snath, a wedge having a corrugated surface interposed between said plate and the

snath and adjustable longitudinally for varying the angle between them, one of said parts having corrugations to interlock with those of the wedge, a scythe blade disposed with its tang against the outer surface of the plate, and a clamping ring encircling the snath and tang with the heel plate and wedge interposed, whereby the clamping action of said ring simultaneously binds all said parts in their adjusted relation.
